Application filed January 31, 1893. Serial No. 460,487. Term of patent 7 years.

To all whom it may concern:

Be it known that I, WARREN E. WARNER, of Rochester, in the county of Monroe and State of New York, have invented and produced a Design for Planting-Dibbles, of which the following is a specification, reference being had to the accompanying drawings, showing the same.

Figure 1 is a side elevation of a dibble constructed in accordance with my design; Fig. 2, an edge view of the same.

The leading feature of my design consists in the shape of the implement, the handle
